US00D583868S

(12) **United States Design Patent**
Peterson

(10) **Patent No.:** **US D583,868 S**
(45) **Date of Patent:** **** Dec. 30, 2008**

(54) **GRIP FOR A WRITING INSTRUMENT**

(75) Inventor: **Frank Peterson**, Lisle, IL (US)

(73) Assignee: **Sanford, L.P.**, Oak Brook, IL (US)

(**) Term: **14 Years**

(21) Appl. No.: **29/284,536**

(22) Filed: **Sep. 10, 2007**

(51) LOC (8) Cl. **19-06**

(52) U.S. Cl. **D19/55**

(58) **Field of Classification Search** .... D19/35, D19/36, 41-51, 53-57; 24/11 F, 11 P, 11 R; 401/52, 99, 100, 104-109, 192, 195, 196

(57) **CLAIM**

The ornamental design for a grip for a writing instrument, as shown and described.

DESCRIPTION

FIG. 1 is a perspective view showing my new design for the grip for a writing instrument;

FIG. 2 is a second perspective view of the grip for a writing instrument of FIG. 1;

FIG. 3 is a side view of the grip for a writing instrument of FIG. 1;

FIG. 4 is a top plan view of the grip for a writing instrument of FIG. 1;

FIG. 5 is a bottom plan view of the grip for a writing instrument of FIG. 1;

FIG. 6 is a perspective view showing my new design for a grip for a writing instrument showing it with a writing instrument;

FIG. 7 is a second perspective view of the grip for a writing instrument of FIG. 6;

FIG. 8 is a side view of the grip for a writing instrument of FIG. 6;

FIG. 9 is another side view of the grip for a writing instrument of FIG. 6;

FIG. 10 is another side view of the grip for a writing instrument of FIG. 6;

FIG. 11 is a top plan view of the grip for a writing instrument of FIG. 6; and,

FIG. 12 is a bottom plan view of the grip for a writing instrument of FIG. 6.

The broken lines showing the inside in FIGS. 1, 2, 4, and 5, and the writing instrument in FIGS. 6 to 12 are shown for environmental purposes only and form no part of the claimed design.
